UNITED STATES PATENT OFFICE

137,411

DESIGN FOR A PICTURE CARRYING PIN OR SIMILAR ARTICLE

George Peyrot, New York, N. Y.

Application December 20, 1943, Serial No. 112,049

Term of patent 7 years

To all whom it may concern:

Be it known That I, George Peyrot, a citizen of the United States, residing in New York city, in the county of New York and State of New York, have invented a new, original, and ornamental Design for a Picture Carrying Pin or Similar Article, of which the following is a specification, reference being had to the accompanying drawing, forming part thereof.

Fig. 1 is a plan view of a picture carrying pin or similar article;

Fig. 2 is the rear view thereof, and
Fig. 3 is an edge view thereof.

I claim:

The ornamental design for a picture carrying pin or similar article, substantially as shown.

GEORGE PEYROT.
